UNITED STATES PATENT OFFICE

138,009

DESIGN FOR A MUFF

Gladys B. Stackhouse, Huntington, N. Y.

Application April 11, 1944, Serial No. 113,216

Term of patent 14 years

(Cl. D3—2)

To all whom it may concern:

Be it known that I, Gladys B. Stackhouse, a citizen of the United States and a resident of Huntington, county of Suffolk and State of New York, have invented a new, original, and ornamental Design for a Muff, of which the following is a specification, reference being had to the accompanying drawing, forming part thereof.

Fig. 1 is a front view of a muff showing my new design,

Fig. 2 is a side view of the muff shown in Fig. 1,

Fig. 3 is a rear view thereof, and

Fig. 4 is a side view of the muff shown in Fig. 1 with the legs and tail on a horizontal plane.

I claim:

The ornamental design for a muff, substantially as shown.

GLADYS B. STACKHOUSE.
